UNITED STATES PATENT OFFICE.

EDWARD LJUNGGREN, OF FAYETTEVILLE, NEW YORK.

MACHINE FOR MAKING DRILLS.

1,302,685.

Specification of Letters Patent.

Patented May 6, 1919.

Application filed November 30, 1917. Serial No. 204,654.

To all whom it may concern:

Be it known that I, EDWARD LJUNGGREN, a citizen of the United States of America, and resident of Fayetteville, in the county 5 of Onondaga, in the State of New York, have invented new and useful Improvements in Machines for Making Drills, of which the following, taken in connection with the accompanying drawings, is a full, clear, and 10 exact description.

This invention relates to certain improvements in machines for making drills and similar implements having spirally shaped grooves or ribs, the object being to produce 15 the drill by forging as distinguished from milling or twisting so as to compress the fiber more firmly and thereby increase its tenacity and strength, and at the same time extending its length, whereby a greater number 20 of drills of a given length are made from the original stock than has heretofore been produced.

Other objects and uses contributory to the main object will be brought out in the following description.

In the drawings—

Figure 1 is a side elevation, partly in section, of a drill-forming machine embodying the various features of my invention.

Fig. 2 is a transverse vertical sectional view taken on line 2—2, Fig. 1.

Fig. 3 is an enlarged detail sectional view taken on line 3—3, Fig. 1.

Fig. 4 is a perspective view of one of the 35 detached dies for forming the drill.

Fig. 5 is an enlarged longitudinal vertical sectional view taken in the plane of line 5—5, Fig. 2.

Figs. 6 and 7 are enlarged transverse vertical sectional views taken, respectively, on lines 6—6 and 7—7, Fig. 1.

Fig. 8 is an enlarged horizontal sectional view taken in the plane of line 8—8, Fig. 2.

As illustrated, the machine comprises an 45 upright standard or frame —1— having a suitable base —2— adapted to rest upon the floor or other support and its upper end provided with a journal bearing —3— for receiving and supporting a revoluble shaft 50 —4— which is also journaled in another bearing —5— on a bracket —6— forming a part of the main supporting frame, but detachably secured thereto by bolts —7—.

The upper half of the bearing —3— is

preferably made separate from the lower 55 portion and is connected to the base by truss rods —3'— to stiffen the frame and transmit the strains on the upper side of the bearing to the base and main body of said frame.

Secured to the outer end of the shaft —4— 60 is a pulley —8— adapted to be connected by a belt to any available source of power, not shown, said shaft being also provided with a balance wheel —9— to steady its action and also to maintain its momentum during 65 the pressing operation of the dies upon the work.

The frame —1— is also provided with vertically alined ways —10— and —11— for receiving and guiding lower and upper vertically movable plungers —12— and —13— which are also arranged in vertical alinement and have their adjacent ends split or divided transversely at —14— to form opposite pairs of yielding jaws. 75

The jaws of each pair are provided with transverse dove-tailed grooves or recesses —15— for receiving and retaining similarly formed portions of a pair of die-holders —16— and are adapted to be drawn together 80 tightly upon the die-holders by clamping bolts —15'—, shown by dotted lines in Fig. 5 and by full lines in Figs. 2 and 6.

The adjacent faces of the die-holders —16— are provided with lengthwise dove-tailed grooves —17— for receiving similarly formed portions of a pair of opposed dies —18— which are provided in their meeting faces with registering lengthwise grooves —19— and diagonally disposed ribs 90 —20—.

These ribs are preferably made of separate pieces of extra-hardened steel and are tightly fitted in corresponding recesses in the bases of the grooves —19— in intersecting 95 planes equi-distant from the meeting faces of the dies when brought together.

The grooves —19— are substantially semi-circular in cross section so that when the dies are closed, they form an opening of circular 100 cross section and of the same diameter as the drill to be formed thereby, the ribs —20— being disposed at equal angles to the axis of said opening, or to their respective grooves so as to cross each other at their 105 central points in said axis or in the longitudinal centers of the grooves.

Each die-holder —16— may also be di-

vided through its longitudinal center to form opposite jaws which may be clamped together by bolts — 21 — in a manner similar to that employed for clamping the die-holders upon the adjacent ends of the plungers.

By clamping the die-holder and dies in the manner described, the screws are always available for loosening or tightening so that the dies may be removed and replaced by others for producing a drill of different size when desired.

A bracket — 22 — is mounted at one end in upright ways — 22' — on the front side of the frame — 1 — and extends forwardly therefrom, its upper side being horizontal and provided with lengthwise ways — 23 — for receiving and guiding a carriage — 24 — which is slideable along said ways at will by means of a handle — 25 — thereon.

20 A rotary work-holder — 26 — is journaled in suitable bearings — 27 — and — 28 — on the carriage — 24 — and comprises a head — 29 — having its hub journaled in the bearing — 27 — and pivoted jaws — 30 — for gripping straight or tapered work, said jaws being operated by toggles — 31 — through the medium of a reciprocating rod — 32 — extending centrally through the head — 29 — and having its outer end journaled in the bearings — 28 — so as to move longitudinally therein.

35 The head — 29 — engages one end of the bearing — 27 — to hold it against endwise movement in one direction, while the hub thereof is provided with a collar — 33 — engaging the adjacent end of the bearing — 27 — to hold the head against movement in the opposite direction, at the same time permitting the head to rotate freely in the bearing — 27 —.

40 A coil spring — 34 — surrounds the shaft or rod — 32 — between the collar — 33 — and an additional collar — 35 — on the shaft — 32 — for retracting the shaft and causing the jaws — 30 — to grip the work as the end of the stock from which the drill, as — a —, is to be made.

45 The means for opening the jaws consists of a hand lever — 36 — fulcrumed at — 37 — upon an extension — 38 — of the bearing — 28 — and engaging the outer end face of a collar — 35 — so that when the handle of the lever is depressed, it will force the shaft — 32 — inwardly against the action of the spring — 34 —, thereby releasing the jaws from the work.

50 The upper portion of the frame — 1 — is provided with laterally projecting lugs — 39 — having recesses — 40 — in which are seated resilient, such as rubber, supports — 41 — for the upper plunger — 13 — which is provided with a cross bar — 42 — extending through vertically elongated openings — 43 — in opposite sides of the adjacent por-

tion of the frame, the opposite end of said cross bar being provided with suitable blocks — 44 — resting upon the upper faces of the resilient supports — 41 —.

The yielding supports for the upper plunger are arranged so as to normally hold the lower faces of the upper die just above the path of movement of the work, as the drill — a —, when held by the work-holder, and at the same time permits the plunger with the dies thereon to be moved downwardly a sufficient distance to produce the necessary hammer blows upon the work for forming the drill.

The means for moving the upper die against the retracting action of the resilient supports — 41 — consists of a rotary disk — 45 — on the outer end of the shaft — 4 — and a series of, in this instance four, hardened cams — 46 — which are inserted in dove-tailed recesses — 47 — in the periphery of said disk uniform distances apart circumferentially, the outer faces of the cams being convex to project slightly beyond the periphery of the disks for engaging a hardened roller — 48 — on the upper end of the plunger — 13 —, as shown more clearly in Figs. 5 and 6.

55 It is now evident that as the disk — 45 — is rotated the plunger — 13 — will be depressed intermittently against the action of the retracting buffers or supports — 41 — to produce the necessary hammer action of the dies upon the work for progressively forming the drill from one end as the work is advanced by the rearward movement of the carriage — 24 —.

60 The drills are formed with opposite spiral grooves running in parallelism in substantially the same manner as twist drills, and in addition to the intermittent hammering of the drill stock for bringing it to the desired form, it is necessary to impart a rotary motion to the work by a uniform speed of rotation of the work-holder with the work therein during the forging operation by the dies, and for this purpose the outer end of the shaft — 32 — is made in the form of a drum of relatively small diameter, around which are several turns — 48 — of a wire cable — 49 — to produce the desired means for turning the shaft as the cable is wound and unwound in opposite directions.

65 After the cable is wound around the reduced end of the shaft — 32 — in the manner described, it is extended laterally in opposite directions over idlers — 50 — on relatively stationary spindles — 51 — on the carriage — 24 —, as shown more clearly in Figs. 5 and 7, and are then extended downwardly around sheaves — 52 — on opposite weights — 53 —, the ends of said wires being then returned upwardly and fastened to their corresponding spindles — 51 — so that the

weights are supported by the wires and are free to move vertically as the cable is wound in opposite directions upon the shaft —32—.

These weights —53— are guided in their 5 vertical movement by rods —54— having their upper ends secured to corresponding sides of the carriage —24— and their lower ends passed loosely through guide openings in the weights, as shown more clearly in

10 Fig. 1.

Suitable means is provided to coöperate with the weights —53— and cables —49— for establishing and maintaining a uniform speed of rotation of the shaft —32— as the 15 carriage with the work-holder and work therein is moved back and forth during the operation of the dies upon the work, said means consisting, in this instance, of a pair of adjustable guides —55— extending longitudinally of the frame in intersecting planes, but at the same angle from a horizontal plane and along and upon which the weights —53— are movable with the carriage —24—, the upper edges of said guides —55— being 20 straight, while the weights —53— are provided with rollers —56— movable along and upon the straight edges of the guides so as to enable the sliding movement of the weights along said guides with a minimum 25 degree of friction.

These guides —55— are pivotally secured at one end by bolts —57— to the bracket —23— at opposite sides of the vertical plane of movement of the weights —53— and incline downwardly in opposite directions 30 from their respective pivotal bolts.

Both of these guides —55— may be adjusted vertically about the axes of their respective pivotal bolts —57—, but vary their 35 degree of inclination which determines the pitch of the spiral grooves in the work and are held in their adjusted position by tightening the pivotal bolt —57—, it being understood that both guides will always be adjusted 40 to the same angle, but incline in opposite directions so that when one weight is moved up the incline of one guide, the other weight will have a corresponding movement down the inclination of the other guide, thereby 45 maintaining a uniform tension upon the wire cable —49— to effect a uniform rotation of the shaft —32— and work-holder thereon.

Each die is adapted to form substantially 50 one-half of the circumference of the drill and, therefore, in beginning their operations upon the work, their respective plungers are adjusted to separate them a sufficient distance to receive such work.

It is, of course, obvious that the impressions made by each die upon the work at each 55 successive blow is only slight and that a considerable number of successive blows are required to make the desired impressions and bring the work to the proper form, and inas-

much as the upper die is returned to its full 60 open position by the yielding supports —41— after each hammer blow by the cams —46—, it is evident that the lower plunger and work-holder with the work therein must be gradually advanced upwardly, but at different speeds;—that of the work holder being advanced at only half the speed as that of the lower plunger.

For this purpose, I have provided a sliding block —60— having a double wedge 75 —61— movable transversely of the frame —1— across the under side of the lower plunger —12— and bracket —22— and resting upon an inclined surface —62— on the base of the frame —1—, as shown more 80 clearly in Figs. 2 and 5.

The incline —62— and lower face of the wedge —61— resting thereon may be of any suitable pitch which would enable the block —60— to ride freely up the incline —62—, 85 but the upper face of the wedge is of a different pitch, in this instance, half of the pitch of its lower face, and is in direct engagement with the under side of the adjacent end of the bracket —22— so as to move 90 said bracket with the carriage —24— and work-holder —26— thereon at substantially half the speed as that of the lower plunger —12— as the block —60— is moved back and forth, the object of which is to gradually 95 advance the dies into the work during the successive hammer blows, it being understood that the difference in relative degrees of movement of the work-holder and lower plunger is to keep the work centrally between 100 the dies and to compensate for the limitations of adjustment of the upper plunger.

The means for reciprocating the sliding block —60— consists of a hand lever —63— fulcrumed at —64— to a lug on the main 105 supporting frame —1— and pivotally connected at —65— to the adjacent end of the block —60—, as shown more clearly in Fig. 2, said block being also provided with a pivoted pawl —66— for engaging ratchet teeth 110 —67— on the base of the frame —1— as the block is advanced up the incline by the lever —63—, said pawl being adapted to be released from its holding position by means of a tripping lever —68— and suitable connections with the pawl, as shown in Fig. 2.

The diameter of the work and depth of formation of the grooves is determined by a limiting stop —69— located in the path of movement of the wedge block —61— which 120 is shown in the position which it assumes when the drill is properly formed.

The operation of the lever —63— is also used to prevent the full return of the upper plunger to its normal position from the resilient supports —41—, after each hammer blow thereon by the cams —46—, and for this purpose the lower end of the lever is

connected by a link —70— to an upright lever —71— which is fulcrumed at —72— upon the main supporting frame —1— and has its upper end connected by a link —73— 5 to a transversely sliding bar —74—.

This bar is movable in ways —75— on the main frame and is provided in its lower edge with a recess —76—, the end walls of which are beveled for engaging a roller —77— on 10 the front face of the upper plunger —14—.

When the dies are in their normal positions for receiving the drill stock between them, the recess —76— is registered with the roller —77— and the wedge block —60— 15 is drawn back from the position shown in the drawings, in which case the handle of the lever —63— would be rocked close to the frame —1—, or stand more closely in an upright position.

20 Now, as the forging operation upon the work by the dies begins, the lever —63— is gradually rocked toward the position shown in Fig. 2, and as one portion of the work is brought more or less closely to the desired form by repeated hammer blows of the 25 upper die, said work is advanced a short distance at a time not greater than the transverse width of the ribs —20— of the dies, this latter movement being accomplished manually by means of the handle —25—, during which the weights —53— are moved by their connections with the carriage —24— along the inclined guides —55—, thus causing a gradual rotation of 30 the work-holder and work therein so that as these operations are continued a spiral groove will be formed in the work, the pitch of which will depend upon the degree of inclination of the guides —55—.

35 40 As the operation of the lever —63— continues, the movement of the wedge —61— of the block —60— will gradually elevate the lower plunger —12— and bracket —23—, while the beveled wall at one end of the recess —76— in the sliding member —74— 45 will ride into the path of return of the roller —77— of the upper plunger —13— to maintain the advanced position of said upper plunger so that the amount of movement of the plunger by the cams gradually becomes less as the dies are pressed into the work.

50 It will be observed that the impression by the dies upon the work at each hammer blow 55 produced by the cams —46— is comparatively slight, yet it is repeated rapidly, and quickly brings that particular portion of the work to the desired form, whereupon the carriage is operated to bring the next adjustment portion of the work into position to be 60 operated upon by the dies, or, the movement of the carriage may begin to advance the work as soon as the dies start to operate thereon, in which case the carriage will be

65 moved back and forth until the entire work is brought to the desired form and size.

In order that the bracket —22— may be 70 more easily moved vertically without binding or excessive friction, its forward end is partially supported by a standard composed of telescoping sections —80— and —81— 75 which are relatively adjustable longitudinally and are held in their adjusted position by clamping bolt —82—, the lower section —80— being adapted to rest upon the floor, while the upper section is movable in a socket —83— in the bracket —22— and is engaged with one end of a spring —84— having its opposite end abutting against the upper wall of the socket, said 80 spring being under sufficient tension to assist the wedge —61— in raising the bracket, and at the same time is sufficiently resilient to yield under the weight of the bracket as 85 the latter is moved downwardly.

While the machine is particularly adapted for making drills of the form commonly known as twist drills, it is evident that it may be used for making any other implements requiring the formation of spiral 90 grooves or ribs.

Furthermore, while the present machine contemplates operating upon stock which has been brought to a white heat, I do not 95 wish to limit myself to its operation upon heated objects, since it is evident that it could be used for forming similar articles of manufacture from cold metal.

What I claim is:

1. In a machine for making drills, the 100 combination of coöperative dies and means for operating one die in relation to the other die, a work-holder and operating means therefor for advancing the work between the dies, means for rotating the work-holder 105 during said advancing movement and means for gradually lessening the movement of the first-named die as the diameter of the work is reduced.

2. In a machine for making drills, the 110 combination with coöperative dies and means for operating one die in relation to the other die, of a work-holder and operating means therefor for advancing the work between the dies, means for rotating the work-holder at 115 uniform speeds as it advances the work between the dies and means for moving said other die step by step toward the first-named die as the diameter of the work is reduced.

3. In a machine of the character described, 120 the combination of coöperative dies, means for moving one die toward and from the other die, a rotary work-holder, a sliding support for the work-holder movable axially thereof to advance the work between the 125 dies, automatic means for rotating the work-holder during the movement of the support, means for gradually lessening the movement

- of the first-named die as the diameter of the work is reduced, and means for moving said other die step by step toward the first-named die during said reduction of the work.
- 5 4. In a machine of the character described, a pair of coöperative dies, one of which is movable toward and from the other, a rotary work-holder, a carriage for the work-holder movable axially thereof to advance the work between the dies, a drum rotating with the work-holder, a cable wound around the drum and operable in reverse directions for rotating the work-holder, weights supported by opposite portions of the cable for 10 tensioning the same, means on the carriage for causing the weights to move therewith, and inclined guides along and upon which the weights are movable as the carriage is moved back and forth, said guides being disposed in intersecting planes at the same angle to the plane of movement of the carriage.
- 15 5. In a machine of the character described, the combination of coöperative dies, a plunger supporting one of the dies, a yielding support for the plunger normally acting to separate its die from the companion die, means for gradually reducing the amount of said separation as the diameter of the work is reduced, a rotary member having a cam acting upon the plunger to force the latter to its pressing position against the action of said yielding support, and means for holding the work between the dies.
- 20 6. In a machine of the character described, the combination of coöperative dies, a plunger supporting one of the dies, a yielding support for the plunger normally acting to separate its die from the companion die, a rotary member having a cam acting upon the plunger to force the latter to its pressing position against the action of said yielding support, a rotary work-holder, means for moving the work-holder axially to advance the work between the dies and means for 25 gradually reducing the movement of said plunger as the diameter of the work is reduced.
- 25 7. In a machine of the character described, the combination of coöperative dies, a plunger supporting one of the dies, a yielding support for the plunger normally acting to separate its die from the companion die, a rotary member having a cam acting upon the plunger to force the latter to its pressing position against the action of said yielding support, a rotary work-holder, means for moving the work-holder axially to advance the work between the dies, automatic means 30 for rotating the work-holder as it is moved axially and automatic means for gradually advancing and holding the second-named die nearer to the first-named die as the diameter of the work is reduced.
- 35 8. In a machine of the character described, the combination of coöperative dies, and separate supports therefor, each movable in relation to the other to bring the dies into pressing coaction upon the work, retracting means for one support, a rotary cam for operating said support against the action of its retracting means, means for gradually advancing and holding the other support nearer to the work as the latter is reduced in diameter, a rotary work-holder, means for moving the work-holder axially to advance the work between the dies, and automatic means for rotating the work-holder as the latter is moved axially.
- 40 9. In a machine of the character described, the combination of a supporting frame, a plunger movable thereon, a die on the plunger, a separate die opposing the first-named die, a sliding wedge engaging the plunger, means for operating the wedge step by step in one direction for gradually moving the plunger toward the work as the latter is reduced by the dies, and means for holding the work between the dies.
- 45 10. In a machine of the character described, coöperative dies, a plunger carrying one of the dies, devices for reciprocating the other die toward and from the work, a rotary work-holder, a carriage therefor movable axially thereof for advancing the work between the dies, a support for the carriage, and means for moving the support step by step at right angles to the direction of movement of the carriage as the work is reduced.
- 50 11. In a machine of the character described, coöperative dies, a plunger carrying one of the dies, devices for reciprocating the other die toward and from the work, a rotary work-holder, a carriage therefor movable axially thereof for advancing the work between the dies, a support for the carriage, and means for moving the support step by step in one direction to keep the axis of the work midway between the dies as said work is reduced in diameter.
- 55 12. In a machine of the character described, a pair of dies having registering longitudinal grooves, and ribs extending diagonally across the grooves in intersecting planes in combination with means for forcing one die toward the other die, rotary means for holding the work between the dies, and means for moving the other die step by step toward the first-named die as the work is reduced in diameter.
- 60 13. In a machine for making drills, the combination of a pair of dies having ribs disposed in intersecting planes, means for rotating the work between the dies, means for intermittently moving one die toward the other die, retracting means for the movable die, and automatic means for gradually

- diminishing the amount of movement of said movable die as the diameter of the work is reduced.
14. In a machine for making drills, the combination of a pair of dies having ribs disposed in intersecting planes, means for intermittently moving one of the dies toward the other die, retracting means for the movable die, automatic means for gradually reducing the retracting movement of said movable die as the diameter of the work is reduced, and means for moving the work back and forth between the dies with a rotary motion.
15. In a machine for making drills, the combination of a rotary workholder having pivoted jaws for gripping straight or tapered work, a pair of dies having diagonal ribs disposed in intersecting planes crossing each other in the produced axis of the workholder, means for moving the workholder axially, means including a hand-lever for opening the jaws of the workholder, a spring for retracting said jaw-opening means, means for rotating the workholder in reverse directions as it is
- 10 16. In a machine for making drills, the combination of a pair of dies, one of which is movable toward and from the other, a carriage movable toward and from the dies, a rotary workholder mounted on the carriage with its axis in substantially the plane of the meeting faces of the dies and comprising a pair of toggle levers at opposite sides of said axis, a pair of jaws pivoted to said levers, a reciprocatory spindle coaxial with the workholder for operating the toggle levers to open and close the jaws, a spring for retracting said spindle to close the jaws upon the work, and a hand-lever for moving the spindle axially against the action of said spring.
- 20 25

In witness whereof I have hereunto set my hand this 17th day of November, 1917.

EDWARD LJUNGGREN.
